Primary Examiner — Katherine A Holbrow*Assistant Examiner* — Riya Salil Kamat(57) **CLAIM**

The ornamental design for a toss game, as shown and described.

DESCRIPTION

FIG. 1 is a perspective view of a toss game showing our new design;

FIG. 2 is a front view thereof;

FIG. 3 is a back view thereof;

FIG. 4 is a left-side elevational view thereof, a right-side elevational view thereof being a mirror image of the left-side elevational view;

FIG. 5 is a top plan view thereof; and,

FIG. 6 is a bottom plan view thereof.

Broken lines in the figures show portions of the toss game that form no part of the claimed design.

1 Claim, 6 Drawing Sheets(56)
